(57) **CLAIM**

The ornamental design for a notebook computer housing, as shown and described.

DESCRIPTION

FIG. 1 is a perspective view of a notebook computer housing of our design shown in an open configuration, broken lines are shown for environmental purposes only and form no part of the claimed design;

FIG. 2 is a top view thereof;

FIG. 3 is a bottom view thereof;

FIG. 4 is a front view thereof;

FIG. 5 is a back view thereof;
FIG. 6 is a right side view thereof;
FIG. 7 is a left side view thereof;
FIG. 8 is a perspective view thereof shown in a closed configuration;
FIG. 9 is a top view thereof;
FIG. 10 is a bottom view thereof;
FIG. 11 is a front view thereof;
FIG. 12 is a back view thereof;
FIG. 13 is a right side view thereof;
FIG. 14 is a left side view thereof;
FIG. 15 is a perspective view of a second embodiment thereof shown in an open configuration;
FIG. 16 is top view thereof;
FIG. 17 is a bottom view thereof;
FIG. 18 is a front view thereof;
FIG. 19 is a back view thereof;
FIG. 20 is a right side view thereof;
FIG. 21 is a left side view thereof;
FIG. 22 is a right front perspective view of a third embodiment thereof shown in a closed configuration;
FIG. 23 is a top view thereof;
FIG. 24 is a bottom view thereof;
FIG. 25 is a front view thereof;

FIG. 26 is a back view thereof;
FIG. 27 is a right side view thereof;
FIG. 28 is a left side view thereof;
FIG. 29 is a right front perspective view of a fourth embodiment thereof in a closed configuration;
FIG. 30 is a left front perspective view thereof;
FIG. 31 is a top view thereof;
FIG. 32 is a bottom view thereof;
FIG. 33 is a front view thereof;
FIG. 34 is a back view thereof;
FIG. 35 is a right side view thereof;
FIG. 36 is a left side view thereof;
FIG. 37 is a left side view of a fifth embodiment thereof shown in a closed configuration wherein the top, bottom, front and back are similar to those of the third embodiment; and,
FIG. 38 is a right side view thereof.
The pairs of closely adjacent, spaced jagged broken lines in the drawings of FIGS. form no part of the claimed design and the portions between such pairs of jagged broken lines are broken away to disclose indeterminate length. Portions of the design that may be visible between the jagged lines have been removed for clarity.
